L. H. TUTT ET AL

LAMP STAND

Filed June 12, 1928

FIG. 1

FIG. 2

INVENTOR.
LEO H. TUTT
EUGENE C. CLARK
BY *E. G. Charles*
ATTORNEY.

UNITED STATES PATENT OFFICE.

LEO H. TUTT AND EUGENE C. CLARK, OF TOPEKA, KANSAS.

DESIGN FOR A LAMP STAND.

Application filed June 12, 1928 Serial No. 27,095. Term of patent 7 years.

To all whom it may concern:

Be it known that we, LEO H. TUTT and EUGENE C. CLARK, citizens of the United States, residing at Topeka, in the county of Shawnee and State of Kansas, have invented a new, original, and ornamental Design for Lamp Stands, of which the following is a specification, reference being had to the accompanying drawing, forming part thereof.

Fig. 1 is a front elevation of my design. Fig. 2 is a side elevation or transverse view of Fig. 1.

We claim: The ornamental design for a lamp stand, as shown.

LEO H. TUTT.
EUGENE C. CLARK.
